Patented Dec. 10, 1918.

UNITED STATES PATENT OFFICE.

ALBERT HERMAN JOHNSON, OF LE MARS, IOWA.

CARPET-BEATER.

1,287,028.

Specification of Letters Patent. Patented Dec. 10, 1918.

Application filed May 21, 1917, Serial No. 169,952. Renewed September 10, 1918. Serial No. 253,471.

To all whom it may concern:

Be it known that I, ALBERT HERMAN JOHNSON, a citizen of the United States, residing at Le Mars, in the county of Plymouth and State of Iowa, have invented a new and useful Carpet-Beater, of which the following is a specification.

The subject of this invention is a carpet beater intended for co-operative association with a vacuum cleaner or sweeper, and the objects of the invention are, first, to provide a rotary carpet beating element, second, to provide beating members yieldingly hung from a moving part, third, to provide means for driving the beater, fourth, to provide a simple and efficient carpet beater.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

A practical embodiment of the invention is shown in the accompanying drawing, wherein:—

90 Figure 1 is a side elevation partly in section of the device attached to a vacuum cleaner.

Fig. 2 is a view in elevation of the beater. The element forming the subject of the present invention consists of a movable support, such as the shaft 1 on which disks 2 are secured. Each disk is provided with a series of apertures 3, two being shown in the present instance. Bail like members 4 are provided and each has its ends bent, as at 5, to take into the apertures 3 and pivotally attach the bail to the disks. Sheaves 6 may be secured to the shaft 1 to form a means for belting the shaft to a suitable source of power.

The device is here shown attached to a vacuum cleaner consisting of a wheel supported casing 7, provided with a handle 8

by which it may be propelled. Within the casing 7 is mounted a motor, not shown, which drives, through suitable gearing, not shown, a fan 9, mounted on the fan shaft 10, and turning within the fan chamber 11. A discharge port 12 is provided for the fan chamber. A sheave 13 is secured on the lower end of the shaft 10 and is connected through a belt 14 to the sheave 6 on the beater shaft.

The beater turns within a cylindrical chamber 15, formed in the casing 7. The chamber 15 is provided at its under side with a longitudinal opening 16 through which the bails 4 are adapted to project.

A dust receiving bag 17 is positioned with its mouth encircling the discharge port 12 and its bottom may be secured to the handle 8, as shown.

It is, of course, understood that any motive power may be employed to drive this device, and the device may be attached to cleaners or sweepers of varying form and design.

In practice the device is used as follows:

The vacuum cleaner is operated in the usual way. The shaft 1 will be driven by the belt 14 causing the bails 4 to be thrown violently against the carpet and beat the same, loosening the dust and dirt, which will then be free to be sucked up by the current of air created by the revolving fan.

Having described my invention, what I claim as new and desire to secure by Letters-Patent is:—

A carpet beater embodying a movable support, a shaft journaled in the support, disks rigid on the shaft and having spaced apertures, bail-like members having bent ends pivotally engaging the apertures secured to the disks, and means for revolving the shaft.

In testimony that I claim the foregoing as my own, I have hereto affixed my signature in the presence of two witnesses.

ALBERT HERMAN JOHNSON.

Witnesses:

T. M. ZINK,
E. BEACHLER.
